No. 36,798.

Patented February 16, 1904.

UNITED STATES PATENT OFFICE.

EGON LOTHAR SCHMITZ, OF NEW YORK, N. Y., ASSIGNOR TO E. FABER PENCIL CO., A CORPORATION OF NEW YORK.

DESIGN FOR A LEAD-PENCIL.

SPECIFICATION forming part of Design No. 36,798, dated February 16, 1904.

Application filed December 10, 1903. Serial No. 184,682. Term of patent 7 years.

To all whom it may concern:

Be it known that I, EGON LOTHAR SCHMITZ, a subject of the Emperor of Germany, residing in the borough of Manhattan, in the city, county, and State of New York, have invented a new, original, and ornamental Design for Lead-Pencils, of which the following is a specification, reference being had to the accompanying drawings, forming part thereof.

Figure 1 is an elevation, and Fig. 2 an end view, showing my new design.

I claim—

The ornamental design for a lead-pencil, substantially as herein shown.

E. LOTHAR SCHMITZ.
